(57) **CLAIM**

The ornamental design for a hinge with worm gear, as shown and described.

DESCRIPTION

FIG. 1 is a front perspective view of the hinge with worm gear according to the present design;

FIG. 2 is a top plan view of the hinge with worm gear of FIG. 1;

FIG. 3 is a bottom plan view of the hinge with worm gear of FIG. 1;

FIG. 4 is a rear elevational view of the hinge with worm gear of FIG. 1;

FIG. 5 is a front elevational view of the hinge with worm gear of FIG. 1;

FIG. 6 is a right-side elevational view of the hinge with worm gear of FIG. 1; and,

FIG. 7 is a left-side elevational view of the hinge with worm gear of FIG. 1.

Phantom lining, where used, is for illustrative purposes only, and forms no part of the claimed design.
